UNITED STATES PATENT OFFICE.

GEORGE HUGHES AND DORWIN F. GIVENS, OF SYRACUSE, NEW YORK.

VALVE-STEM.

1,163,927.

Specification of Letters Patent. Patented Dec. 14, 1915.

Application filed July 22, 1915. Serial No. 41,299.

To all whom it may concern:

Be it known that we, GEORGE HUGHES and DORWIN F. GIVENS, citizens of the United States, residing at Syracuse, in the county of 5 Onondaga and State of New York, have invented certain new and useful improvements in Valve-Stems; and we do declare the following to be a full, clear, and exact 10 description of the invention, such as will enable others skilled in the art, to which it appertains to make and use the same.

This invention relates to the general class known as valves and relates broadly to a new and improved valve that incorporates 15 in the valve structure means for holding the valve in open position.

Another object of this invention is to provide a valve of this character which is applicable for use on bicycle or automobile tires, 20 and the like, where the valve may be held open by the said means to allow the free ingress and egress of air during the inflation of the tire, where formerly the pump had to hold the valve open during the operation. 25

A further object of the invention is the provision of a valve of this character which is simple and durable in construction, inexpensive to manufacture and one which will 30 be very efficient in operation.

With these and numerous other objects in view our invention consists of the novel features of construction, combination and arrangement of parts, which will be herein referred to and more particularly pointed out in the specification and claim.

Figure 1 is a central vertical section showing the valve in closed position; Fig. 2 is the same, showing the valve held in open position 40 and a supply pipe from a pump attached thereto; and Fig. 3 is a horizontal section taken on the line 3—3 of Fig. 1.

In describing our invention we shall refer to the accompanying drawings in which 45 similar reference characters designate corresponding parts throughout the several views and in which the numerals 1 and 2 designate a valve casing of the usual form, the lower end of the casing 2 being attached 50 to the tire in the manner usual to devices of this character. The two parts 1 and 2 of this casing are secured as shown at 3 in the drawing and have spaced therein a cone-shaped valve 4 with the washer 5 on its 55 lower end positioned on a lug 6 projecting

from the lower end of the valve 4. Spaced below the lower end of the valve 4 in the casing 2 is a stop shoulder 8 and positioned between the stop shoulder 8 and the washer 5 on the lower end of said valve in a coil 60 spring 7 which is compressed and normally tends to hold the valve 4 in a closed position as is shown in Fig. 1 of the drawing.

The valve 4 has projecting upwardly from its upper end through the upper end of the casing 1, a stem 9, which has a restricted 65 upper end 10. An annular shoulder 11 is formed where the upper end of the stem 9 is restricted for a purpose to be hereinafter more fully described.

Positioned in the upper end of the casing 1 and adjacent the top of the same is a spider 12 having a plurality of openings 13 and a central aperture 14 therethrough. A cap 15 is adapted to be placed over the upper end of the casing when the valve is not 70 in use for a purpose which will be obvious.

In operation when the parts of this valve are positioned as shown in Fig. 1 of the drawing, it will be seen that the stem 9 of 80 the valve projects upwardly through the casing and has its upper restricted end 10 projecting therefrom. The valve will normally be held in this position by the constant upward pressure of the spring 7 bearing 85 against its lower surface and the parts positioned as above shown. When it is desired to open this valve for any reason, such as for instance, to inflate the tire, the upper end 10 of the stem 9 is depressed or pushed 90 downwardly until the shoulder 11 is positioned below the aperture 14 in the spider 12 in the casing 1. The stem is then pushed radially in any direction, and released whereby the pressure of the coil spring 7 95 will force the shoulder 11 against the lower side of the spider 12 and hold the same, consequently holding the valve in open position.

To release the valve it is simply necessary to move the restricted end 10 of the stem 9 into vertical alignment with the aperture 14 in the spider whereby the shoulder 11 will be released from beneath the stem and the spring 7 will force the valve back to its normal closed position. The spider 12 in 100 the upper end of the casing 1, as will thus be seen, acts as a stop to hold the valve open when compressed, and also as a guide for the stem during the opening and closing of 105 said valve.

The essential feature of this invention is the action between the stem of the normally actuated closed valve and the spider or stop in the top of the casing 1 to hold the valve in open position, the advantage of which is obvious.

Formerly when using a valve of this character in the inflation of a tire or the like, it was necessary for the pump to overcome the pressure of the spring in the valve to hold the same open, but by the use of the novel means above described, the valve is held in open position and is easily and simply disengaged therefrom when the pumping operation is completed.

This valve is also especially adapted for use as a deflator in case of small punctures. Formerly when it became necessary to take the shoe off to change the inner tube of the tire, it was necessary to take the valve out, or hold it down in rolling up the inner tube, but by the use of our improved valve it is only necessary to push the stem of the valve down and move it radially to lock the same in operative position whereby when the inner tube is rolled up, the air is free to pass out.

From the above description and explanation of the parts of this valve it will be seen that a valve of this character which involves a feature for releasing air, which is incorporated in the valve 6, thereby eliminates the use of a separate article to accomplish this purpose.

From the foregoing description of the construction of our improved valve and the manner of applying the same to use, to a vehicle tire or automobile tire, or the like, and the operation thereof, it will be readily seen

that we have provided a very simple means for carrying out the objects of the invention.

While we have particularly described the elements best adapted to perform the functions set forth, it is obvious that various changes in form, proportion, and in the minor details of construction may be resorted to within the scope of the appended claim, without departing from or sacrificing any of the principles of this invention.

We claim as our invention:

A device of the character described comprising a tubular casing, a longitudinally movable spring actuated normally closed valve therein, a stem projecting from said valve through one end of the casing adapted for inward movement of the same against the spring to open the valve, said stem being smaller than the bore of the casing and having an outwardly projecting portion restricted to form a shoulder thereon adjacent its free end, and a spider in said casing below the shoulder on the stem having a central opening therethrough slidably engaged with the stem, whereby when the shoulder is pushed inwardly in alignment with the inner surface of the spider, moved radially and then released, the shoulder of the stem will lock with the inner surface of the spider and hold the valve open.

In testimony whereof we have hereunto set our hands in presence of two subscribing witnesses.

GEORGE HUGHES.
DORWIN F. GIVENS.
